PLAYING CARD RACK

Clifford L. La Jeunesse, Milwaukee, Wis.

Application September 8, 1949, Serial No. 4,903

Term of patent 14 years

(Cl. D34—13)

To all whom it may concern:

Be it known that I, Clifford L. La Jeunesse, a citizen of the United States, residing at Milwaukee, in the county of Milwaukee and State of Wisconsin, have invented a new, original, and ornamental Design for a Playing Card Rack, of which the following is a specification, reference being had to the accompanying drawing, forming part thereof.

Fig. 1 is a top plan view of a playing card rack showing my new design;

Fig. 2 is a bottom plan view of the playing card rack illustrated in Fig. 1;

Fig. 3 is a view in side elevation;

Fig. 4 is a view in end elevation;

Fig. 5 is a view taken in section on the line 5—5 of Fig. 1;

Fig. 6 is a fragmentary view taken in section on the line 6—6 of Fig. 1; and

Fig. 7 is a fragmentary view taken in section on the line 7—7 of Fig. 1.

I claim:

The ornamental design for a playing card rack, as shown.

CLIFFORD L. LA JEUNESSE.
